UNITED STATES PATENT OFFICE.

EMMET C. WEBER, OF OWATONNA, MINNESOTA.

WASHING-MACHINE.

SPECIFICATION forming part of Letters Patent No. 344,700, dated June 29, 1886.

Application filed July 17, 1885. Serial No. 171,861. (Model.)

To all whom it may concern:

Be it known that I, EMMET C. WEBER, a citizen of the United States, residing at Owatonna, in the county of Steele and State of Minnesota, 5 have invented certain new and useful Improvements in Washing-Machines, of which the following is a specification, reference being had therein to the accompanying drawings.

Figure 1 is a perspective view of this device. Fig. 2 is a detail in section of the vessel or tub and the support secured thereto. Fig. 3 is a detail in central vertical section of the shaft to which the pounders are attached. Fig. 4 is a detail central section vertically 15 through one of the pounders. Fig. 5 is a detail in perspective of the tub and pounder support.

This invention relates to that class of washing-machines known more particularly as 20 "beaters" or "pounders;" and the novelty consists in the construction and combination of the several parts, all as will now be more fully set forth and claimed.

In the accompanying drawings, A represents the tub or vessel for the water, and in which the beating or pounding operations are carried on. On one side to the edge or rim of A is attached the support B by means of its two pairs of depending legs, b b'. Each pair 25 straddles the rim, the longer leg, b, of each pair coming inside the tub, and the shorter one, b', outside. The set-screws b² in the outer legs clamp the support firmly to the tub. This construction insures a firm fastening. In the upper face of the support is a dovetail groove, b³, in which slides the lower and horizontal part, c, of the base C, which gives support to the operative parts of the device. The part c is fixed firmly upon the support B by set-screw 30 c', which passes through the slot b⁴ in this part. By this construction the base C can be placed in any desired relation to the edge of the tub to secure in tubs of varying sizes a central position of the pounders in the tub. It is not 35 absolutely necessary to have the dovetails, but they afford a very convenient and steady guide.

On each side of the vertical part c² of the base C are pivoted the ends of arms d of the handle D. The other end of said handle extends over the opposite edge of the tub. Between these arms and centrally in the tub is

pivoted, by gimbals e, the sleeve E, in which the vertical shaft F may be horizontally turned or by means of which it can be swung to or fro. Below the gimbals e the pounder-arms g 55 are radially fixed to the shaft F. At the lower end of the shaft F is fixed one of the pounders, G', and to the ends of each of the radial arms g is secured a pounder, G, by means of the neck g', which projects through horizontal slot 60 g², and is held in any desired horizontal position in said slot by thumb-nut g³. All the pounders or beaters are inverted-cup shape, cylindrical, or elliptical, and are secured to their neck g' by the internal conically-shaped 65 piece g⁴, which screwed on the lower end of the neck g' clamps the open apex of the pounder between it and the flange g⁵, or these parts may be soldered together. There may be as many of these radial pounders as are desired. When 70 the shaft F is raised by the handle D, the pawl h on the arm H, attached to the handle, acting on the annular rack I on the shaft F forces the shaft to turn a short distance. The lowering of the arm retracts the pawl and puts it in 75 position to meet and engage on the next tooth of the rack when the arm D is again raised. Thus rotary motion to the radial pounders may be obtained. In its higher upward movement the upper end of the pawl-arm H strikes against 80 and raises the flaring projection k of the arm K, which projects partially over the tub, and at its rear end is pivoted to the part e² of the base C some distance above the arm d. By thus raising the arm K it is released from its confinement by the pin e² on the upper free end 85 of arm e', attached to the sleeve E in the end of the rectangular slot k', and this release permits the shaft F to swing a little when the arm d is at its highest elevation, allowing the pounders to tip, so that they can be raised out of the tub and thrown back until the handle rests on the pieces c² projecting from the vertical piece c², and will remain in that position by its weight. In this position it is easy to put the 90 clothes, &c., into or take them from the tub; but in the ordinary movements of the mechanism the slotted arm k and pin e² serve to hold the upper end of shaft F vertical. The beaters may have any desired configuration.

The handle D and arms d may be made in one piece or in several, and otherwise in the

more mechanical detail I may make changes without in any degree departing from the nature and scope my invention.

The sleeve E can be adjusted up or down on shaft F by means of set-screw x.

What I consider new, and desire to secure by Letters Patent, is—

1. In a washing-machine, the vertical and revoluble shaft F, having pounders, as described, attached to its lower end, combined with the sleeve E, having the vertical arm e', provided with the pin e², the slotted arm K, the standard C, the support B; and the handle D, substantially as described.

2. In a washing-machine, the combination of the vertical shaft F and handle D with the arms d and K, the standard C, and the sup-

port B, having dovetail grooves b³, slot b⁴, legs b b', and set-screws b² and c', all substantially as described.

3. The combination, in a washing-machine, of the support B, the standard C, the arms d, the arm K, slotted at k' and having projection k, the vertical shaft provided with pounders G G', the sleeve E, the annular rack I, the set-screw x, and the handle D, having the upwardly-extending arm H, pivoted with the pawl h, as and for the purposes set forth.

In testimony whereof I affix my signature in presence of two witnesses.

EMMET C. WEBER.
